ELECTRICAL CONNECTER

Walter M. Hill, Baltimore, Md., assignor to
Western Electric Company, Incorporated, New
York, N. Y., a corporation of New York

Application September 27, 1930, Serial No. 484,793

3 Claims. (Cl. 173—324)

This invention relates to electrical connectors, and more particularly to a grounding terminal and clamp for insulated conductors.

An object of the invention is to provide an electrical connector of simple and inexpensive construction which may be expeditiously clamped and electrically connected to an insulated conductor without removing any of the insulation therefrom.

10 One embodiment of the invention contemplates the provision of a grounding terminal and clamp for insulated electrical conductors, comprising opposed fixed and movable contact blades, the latter being carried by a pivoted arm and movable 15 to open and closed positions with respect to the fixed contact blade through the rotation of an operating pin having an eccentric portion extending through a slot in the pivoted arm. The contact blades are adapted to penetrate or cut 20 through the insulation of a conductor interposed therebetween, and become slightly embedded in the conductor, whereby a good electrical connection, as well as a satisfactory clamping of the conductor, is secured without removing any of 25 the insulation from the conductor. The movable contact blade is adapted to be locked in open or closed positions by means of a leaf spring arranged 30 to engage either of two diametrically opposed peripheral notches in an enlarged circular head portion of the operating pin. The fixed contact blade is adjustable to accommodate conductors of various sizes.

Other features and advantages of the invention will become apparent from the following detailed 35 description, reference being had to the accompanying drawing, wherein

Fig. 1 is a plan view of a grounding terminal and clamp embodying the features of the invention;

40 Fig. 2 is a vertical sectional view on line 2—2 of Fig. 1;

Fig. 3 is a sectional view similar to Fig. 2 with the movable contact blade shown in its open position; and

45 Fig. 4 is a vertical sectional view on line 4—4 of Fig. 1.

Referring now to the drawing, in which like reference numerals designate the same parts in the several views, it will be observed that a metallic frame or base 10 is formed with an open 50 right angle slot or bifurcation 11 which is of rectangular cross section and extends along the upper side of the frame and downwardly along an adjacent vertical side thereof. A pair of co- 55 operating knife edged metallic gripping members

or contact blades 12 and 13 are mounted within the slot 11 with their knife edges in opposed spaced relationship, as shown in Figs. 2 and 3. The contact blade 12 is fixed to the frame 10 by means of a screw 15 threaded in the frame. The screw 15 extends through an elongated aperture 16 in the contact blade, whereby the latter is adjustable with respect to the cooperating oppositely disposed contact blade 13. This adjustment is facilitated by an adjusting screw 18 60 threaded in the frame which abuts against the bottom or far end of the contact blade 12 and is provided with a lock-nut 19, whereby it is secured in an adjusted position. It will be understood that the contact blade 12 may be readily adjusted 65 with respect to the contact blade 13 by loosening the screw 15 and lock-nut 19, and then turning the adjusting screw 18.

The contact blade 13 is formed with an integral portion 21 extending at right angles therefrom 70 by means of which it is secured by screws 22 to one end of an arm 24, the latter being pivoted at its opposite end upon a pin 25 mounted in the frame. Means is provided for moving the arm 24 about its pivot 25 to open and close the contact blade 13 with respect to the contact blade 12. This means comprises an operating member or pin 27 rotatably mounted in the frame 10 and having an eccentric portion 28 extending through an elongated slot 29 formed in the pivoted arm 80 24. The construction is such that through the rotation of the operating pin 27, the contact blade 13 is moved by the eccentric portion 28 of the pin toward or away from the contact blade 12 according to the direction of rotation of the 85 pin. A hand lever 30 is attached to an enlarged circular head 31 formed at one end of the operating pin 27 and serves as a means for rotating the pin to open and close the contact blade 13. The circular head 31 is provided with diametrically 90 opposed V-shaped peripheral notches or slots 32—32 adapted to be selectively engaged by a correspondingly shaped bead 33 formed at one end of a leaf spring 35 to lock the movable contact blade 13 in its open or closed positions. At 95 its opposite end, the leaf spring 35 has a portion 36 (Fig. 4) extending perpendicularly therefrom whereby it is clamped between a block 38 and a side of the frame 10 by means of screws 39—39.

The above described grounding terminal and clamp may be employed advantageously in conjunction with apparatus for coiling and simultaneously testing insulated conductors, such as two or more parallel wires 40—40 having a common covering 42 of rubber compound or other in- 110

sulating material. When employed in this manner, the frame 10 is attached in any suitable manner to a coiler or take-up reel (not shown) upon which the conductors are to be coiled. The 5 fixed contact blade 12 is adjusted so that the space between it and the cooperating movable contact blade 13, when the latter is in closed position, is slightly less than the diameter of the wires 40, after which the movable contact blade 10 is opened or moved away from the fixed contact blade by turning the hand lever 30 from the position shown in Fig. 2 to the position shown in Fig. 3. After the end of the insulated twin wires 15 is inserted between the contact blades, as shown in Fig. 3, the movable contact blade 13 is closed or moved toward the fixed contact blade 12 by turning the hand lever 30 from the position shown in Fig. 3 to the position shown in Fig. 2. This causes both contact blades to penetrate or cut 20 through the insulation 42 and become slightly embedded in the wires 40, thus insuring a good electrical connection with the wires without removing any of the insulation therefrom. A satisfactory clamping of the wires for starting the 25 coiling operation is also secured by reason of the jaws becoming embedded in the wires. The movable contact blade is automatically locked in its closed position by the engagement of the bead 33 of leaf spring 35 with one of the V-shaped 30 notches 32 in the head 31 of the operating pin 27. When desired, the end of the insulated wires may be readily disengaged from the grounding clamp by turning the hand lever 30 from the position shown in Fig. 2 to the position shown in Fig. 3.

35 It will be understood that the embodiment of the invention herein illustrated and described merely represents one useful form of the invention which is capable of numerous modifications within the scope of the appended claims.

40 What is claimed is:

1. A clamping device, comprising a frame having an open slot, an arm pivoted in the slot, a gripping member carried by the arm, a fixed gripping member mounted in the slot opposite

the first gripping member, means for adjusting the fixed gripping member with respect to the pivotally supported gripping member, a pin rotatable in the frame and having an eccentric portion for cooperating with the pivoted arm to move the associated gripping member with respect to the fixed gripping member, the rotatable pin having an enlarged head portion provided with a peripheral notch, and a leaf spring for engaging said notch to lock the movable gripping member to a predetermined position with respect to the fixed gripping member.

2. In a combination electrical connector and clamp, a metal frame, a metallic electrically connecting and mechanically clamping blade adjustably mounted thereon, a metallic swinging member provided with a slot pivotally mounted on the frame, a second metallic electrically connecting and mechanically clamping blade adjustably mounted on the swinging member for coaction with the first mentioned blade, and operating means to force the two blades into operative relation, said operating means including a rotatable shaft mounted in the frame and having an eccentric portion extending through and adapted to coact with the walls of said slot formed in the swinging member, and all said parts being in mutual electrical communication.

3. In a combination electrical connector and clamp for conductors, a metal frame, a metallic electrically connecting and mechanically clamping blade thereon, a metallic swinging member pivotally mounted on the frame, a second metallic electrically connecting and mechanically clamping blade mounted on the member adapted to swing therewith to coact with the first mentioned blade, operating means to embed the two blades into the conductor forming an electrical and mechanical clamping connection with the conductor comprising an eccentric shaft cooperating with the swinging member, and a spring locking member to lock the blades in operating position.
